UNITED STATES PATENT OFFICE.

WILLIAM A. SMITH, OF DENVER, COLORADO, ASSIGNOR TO THE DENVER ROCK DRILL MANUFACTURING COMPANY, OF DENVER, COLORADO, A CORPORATION OF DELAWARE.

ROCK-DRILL SHARPENER.

1,270,667.

Specification of Letters Patent. Patented June 25, 1918.

Application filed June 13, 1917. Serial No. 174,580.

To all whom it may concern:

Be it known that I, WILLIAM A. SMITH, a citizen of the United States, residing at Denver, in the county of Denver and State 5 of Colorado, have invented certain new and useful Improvements in Rock-Drill Sharp- eners, of which the following is a specifica- tion.

The present invention relates to rock drill 10 sharpening apparatus, and more especially to certain improvements in mechanism of the type disclosed in my Patent, No. 1,233,723 dated July 17, 1917.

The primary object of the present in- 15 vention is to provide mechanism of a simple compact character that will effect a quick opening movement of the gripping jaws.

The preferred embodiment of the in- 20 vention is illustrated in the accompanying drawings, wherein:—

Figure 1 is a view partially in elevation and partially in section of the apparatus.

Fig. 2 is a detail sectional view through the return plunger and its cylinder.

Fig. 3 is a rear elevation of the same.

Fig. 4 is a detail sectional view on the line 4—4 of Fig. 1.

Similar reference numerals designate cor- 25 responding parts in all the figures of the drawings.

In the embodiment illustrated, a suitable base 5 is employed, from which rise spaced standards 6. These standards are connected by a cross pin 7 that is held against turning 30 and accidental detachment by a set screw 8. Journaled on the pin 7 and located between the standards 6 is a lever 9, one arm of this lever having a suitable gripping jaw 10 coöperating with a stationary jaw 11 carried 35 by the standards, the other arm of the lever having a pivotal connection 12 with a rod 13 of a piston 14 that operates in a vertical cylinder 15 fixed upon the base 5. Projecting from one side of the standards is a hori- 40 zontal arm 16 which supports the dollying mechanism, not shown.

Motive fluid for the apparatus is sup- 45 plied from any suitable source through a hose line 17 having a branch 18 connected to a valve mechanism 19 by which the supply of fluid to the cylinder 15 and to the dollying mechanism is controlled. The apparatus as thus far described, is disclosed in the afore-

said patent, and no claim is herein made to this mechanism.

In order to secure a quick opening move- 55 ment to the jaws 10 and 11 by swinging the lever so that the arm carrying the jaw 10 will rise quickly from the jaw 11, the follow- ing mechanism is preferably employed. The 60 lever 9 is provided with a third depending arm or projection 20, the rear side of which is rounded as illustrated at 21 and bearing against said rounded side is one end of a plunger 22 that is slidably mounted in a 65 horizontal cylinder 23. The cylinder 23, piston or plunger 22 and the arm 20 are all disposed between the standards 6, and said cylinder is preferably mounted by having a rear head 23^a in the form of a flange that is 70 bolted, as illustrated at 24, to said standard 6. The rear end of the plunger 22 is pro- 75 vided with suitable packing 25, and motive fluid is supplied to the cylinder 23 behind said plunger by means of a branch pipe 26 connected to the hose line 17, as shown at 27, this pipe being also connected to the rear head 23^a.

With this construction, it will be evident 80 that while motive fluid is constantly acting against the plunger 22 and said plunger is thus constantly tending to swing the jaws to relatively open position, whenever motive fluid is admitted to the cylinder 15 beneath the piston 14, the latter having a very much 85 greater area than the piston 22—25, the jaws will be closed upon the work with sufficient force to hold the drill during the dollying operation.

From the foregoing, it is thought that the 90 construction, operation and many advan- tages of the herein described invention will be apparent to those skilled in the art, with- out further description, and it will be under- 95 stood that various changes in the size, shape, proportion and minor details of construction, may be resorted to without de- parting from the spirit or sacrificing any of the advantages of the invention.

Having thus fully described my invention, 100 what I claim as new, and desire to secure by Letters Patent, is:—

1. In drill sharpening apparatus of the character described, the combination with work gripping mechanism including a 105 swinging member, of fluid actuated means

for moving the member to grip the work, and means bearing directly against the member to open the apparatus when the means for moving it to gripping position is inactive.

2. In drill sharpening apparatus of the character described, the combination with a work gripping mechanism including a swinging member, of fluid actuated means for moving the member to grip the work, and fluid actuated means of less power having a portion bearing against the member and constantly acting to open the apparatus when the means for moving it to gripping position is inactive.

3. In drill sharpening apparatus of the character described, the combination with work gripping mechanism including a swinging member having three arms, one of said arms having a gripping jaw, of means engaged with another arm for swinging the member to cause the jaw to grip the work, and means engaged with the third arm to swing the member out of gripping relation with the work.

4. In drill sharpening apparatus of the character described, the combination with work gripping mechanism including a swinging member having three arms, one of said arms having a gripping jaw, of fluid actuated means engaged with another arm for swinging the member to cause the jaw to grip the work, and fluid actuated means

engaged with the third arm to swing the member out of gripping relation with the work.

5. In drill sharpening apparatus of the character described, the combination with a base having spaced standards rising therefrom, of a lever pivoted between its ends to and between the standards, one arm of said lever constituting a gripping jaw, fluid actuated means on the base connected to the other arm of the lever to move said lever in one direction, said lever also having a depending projection between the standards, and fluid actuated means mounted between the standards and operating on the depending projection to move the lever in an opposite direction.

6. In drill sharpening apparatus of the character described, the combination with a base, of a swinging lever fulcrumed thereon, coacting jaws, one of which is carried by the lever, cylinders of different capacities mounted on the base in angular relation to each other, pistons in the cylinders, and means operated by the pistons for respectively moving the lever in different directions.

In testimony whereof, I affix my signature in the presence of two witnesses.

WILLIAM A. SMITH.
